UNITED STATES PATENT OFFICE.

WILLIAM S. BECHTOLD, OF NEWARK, NEW JERSEY.

DESIGN FOR A BACK COMB OR SIMILAR ARTICLE.

60,302.

Specification for Design.

Patented Feb. 7, 1922.

Application filed April 29, 1921. Serial No. 465,545. Term of patent 3½ years.

To all whom it may concern:

Be it known that I, WILLIAM S. BECHTOLD, a citizen of the United States, residing at Newark, in the county of Essex and State of New Jersey, have invented a new, original, and ornamental Design for Back Combs or Similar Articles, of which the following is a specification, reference being had to the accompanying drawing, forming part thereof.

The figure is a view in elevation of a back comb, showing my design. The design shown is applicable, also, to barrettes and braid pins.

I claim:

The ornamental design for a back comb or similar article, as shown.

WILLIAM S. BECHTOLD.
